UNITED STATES PATENT OFFICE.

STEPHEN D. BAKER, OF NEW YORK, N. Y.

DESIGN FOR A COMBINATION BATHROOM FIXTURE.

Application filed December 31, 1921. Serial No. 526,387. Term of patent 14 years.

To all whom it may concern:

Be it known that I, STEPHEN D. BAKER, a citizen of the United States, and a resident of New York city, in the county of New York and State of New York, have invented a new, original, and ornamental Design for a Combination Bathroom Fixture, of which the following is a specification, reference being had to the accompanying drawings, forming part thereof.

The figure in the accompanying drawing shows in a perspective view, a combined tumbler, soap and tooth brush holder embodying my new design.

I claim:

The ornamental design for a combination bathroom fixture, as shown.

STEPHEN D. BAKER.
